FIG. 6

UNITED STATES PATENT OFFICE

2,267,481

PNEUMATIC THREAD HOLDER FOR LOOMS

Richard G. Turner, Worcester, Mass., assignor to
Crompton & Knowles Loom Works, Worcester,
Mass., a corporation of Massachusetts

Application January 4, 1940, Serial No. 312,394

11 Claims. (Cl. 139—247)

This invention relates to pneumatic thread holders for looms and it is the general object of the invention to provide a holder of this type having an inherently resilient thread receiver which will yield at the time of transfer and for the pick of the shuttle immediately thereafter to prevent thread breakage.

In my prior Patent No. 2,199,353 I have set forth a pneumatic thread holder having an intake mouth to receive threads extending from the reserve bobbins of a magazine. In that application and also in another Patent No. 2,199,354 the threads are led to a metallic receiver and into a soft rubber tube held by a rigid holder. In weft replenishing mechanisms of the multi-color type the bobbins descend in the magazine toward a transfer position. At the time of transfer the bobbin is subjected to a sudden downward motion into the shuttle with attendant strain on the thread extending from it into the thread holder. If this strain is sufficient to break the thread the loom will stop on the next pick after transfer. Even if the thread remains intact during transfer it is subjected to a second strain at the time of picking due to the fact that the shuttle eye is not yet threaded. Under either of these conditions it is desirable that the thread shall be free to yield sufficiently to relieve any strains incident either to transfer or picking.

It is an important object of my present invention to provide a thread holder having a yieldable part which is normally extended in a direction transverse of the threads leading from the reserve bobbins but movable toward the magazine in response to strains in the thread to prevent breakage of the latter.

At the time of picking the thread of the freshly transferred bobbin extending into the thread holder is subjected to a strain tending to pull it out of the thread holder. It is a further object of my present invention to provide the thread holder with a portion which will bend in such a direction as to increase the frictional contact between the thread of the freshly transferred bobbin and the thread holder. The extent of the bending will depend upon the amount of the strain, a relatively large thread strain causing sufficient bending of the thread holder part to insure contact therewith of a considerable length of thread. These results I may achieve by using a soft rubber tube projecting from a support and bendable toward the magazine.

Many looms are provided with a so-called center filling stop motion having a fork carried on the lay to be lowered on the thread during the

forward beat of the lay. It is desirable that the thread of the freshly transferred bobbin be led under the fork to insure continued loom operation and it is a further object of my present invention to provide a yieldable thread holder which will act during the flight of the shuttle across the loom to move the thread forwardly and thereby assist in placing it under the filling fork.

It is a further object of my invention to mount one end of a resilient tube on a thread holder and permit the other end to extend freely without support so that it will vibrate under loom operation and have the effect of spacing the thread ends which enter it.

With these and other objects in view which will appear as the description proceeds, my invention resides in the combination and arrangement of parts hereinafter described and set forth.

In the accompanying drawing, wherein a convenient embodiment of my invention is set forth,

Fig. 1 is a front elevation of a portion of a magazine and pneumatic thread holder made according to my present invention,

Fig. 2 is a horizontal section on line 2—2 of Fig. 1,

Fig. 3 is a detail vertical section on line 3—3 of Fig. 2,

Fig. 4 is an enlarged front elevation of the tube forming an important part of my present invention,

Figs. 5 and 6 are diagrammatic plan views of the lay showing the action of my thread holder during flight of the shuttle on the first pick after transfer,

Fig. 7 is an enlarged horizontal section through the flexible tube illustrating the manner in which the same bends to increase frictional contact with the thread attached to the bobbin being transferred, and

Fig. 8 is a detail side elevation of the yielding tube and thread guard looking in the direction of arrow 8, Fig. 1.

Referring to Fig. 1, I have shown a reserve bobbin magazine M having reserve bobbins B therein from which extend weft ends W. The bobbins descend in well-known manner toward a transfer position where they are pushed into a depleted shuttle by well known transfer mechanism not shown herein but operating in the usual manner. A thread accumulator A may comprise a hollow cylinder 10 carried by a fixed support 11 held in any approved manner by the magazine. The interior of the cylinder 10 communicates by means of a hose 12 with a pump not shown but

set forth in my patents previously mentioned and effective to create sub-atmospheric pressures within the cylinder 10.

As shown diagrammatically in Figs. 5 and 6 the loom L comprises a breast beam 15 and a lay 16 which reciprocates in usual manner toward and from the breast beam. A shuttle S is picked by well-known mechanism back and forth across the lay, a picker 17 being shown in Fig. 5 for this purpose. A fixed air pump 18 is driven from the lay as by a connector 19 and is attached to the tube 12 so that during reciprocation of the lay sub-atmospheric pressures will be created in the tube 12 and in the accumulator on the backward stroke of the lay, all as set forth in my previously mentioned patents. A filling fork 20 of the usual construction has rearwardly extending tines 21 located between the selvages of the cloth designated at C. The reed 22 guides the shuttle across the loom and the tines 21 terminate a short distance in front of the reed.

The matter thus far described may be of the usual construction and operate in the usual manner. The sub-atmospheric pressures existing within the cylinder 10 will be created periodically although I am not limited in the practice of my invention to this particular procedure and the bobbins will descend to transfer position one by one. At the time of transfer the bobbin in transfer position will be pushed into the shuttle S by a downward motion which is likely to stress its weft end W. Very shortly after transfer the shuttle will be picked to the opposite or left hand side of the loom, as viewed in Figs. 5 and 6, and the thread will again be subjected to a stress created by motion of the shuttle away from the magazine end of the loom.

In carrying my invention into effect I provide a form of inlet for the thread accumulator which can yield in response to the strains set up in the weft thread of the freshly transferred bobbin existing both at the time of transfer and the immediately ensuing pick. In carrying my invention into effect I provide the base 30 of the accumulator which is supported by the stand 11 with a bore 31 extending horizontally forwardly and insert into this bore a flexible soft rubber tube 32. The rear end of the bore may be inclined upwardly as at 33 to produce a slight upward curvature in the rear or right end of the tube 32 as viewed in Fig. 3. The forward end of the tube projects forwardly from the base and has the bore 34 thereof reduced slightly at its mouth 35 by an internal rim or flange designated at 36 for the purpose of requiring any threads which enter the mouth and extend toward the accumulator to have a portion of their length spaced from the adjacent interior walls of the tube.

A thread guard designated at 40 has a foot 41 extending along and secured to the base 30 as by a screw 42. The guard extends forwardly and has a horizontal platform 43 from one side of which project upwardly a pair of spaced horns 44 defining between them a thread receiving notch 45. The relation between these notches and the end of tube 32 may be as set forth in Fig. 8, and it is to be understood from an inspection of Fig. 1 that the horns are located on that side of the tube opposite the magazine where they will not interfere with any flexing of the tube toward the reserve bobbins.

In operation, after fresh bobbins have been inserted into the magazine, the operator will lay the weft ends W in the notch 45 and they will

be drawn into the mouth 35 by suction. The threads will ordinarily and preferably be long enough to extend into the cylinder 10 to become entangled with a mass of yarn Y located within the cylinder 10 as set forth in my previously mentioned Patent No. 2,199,354. The horns 44 are sufficiently wide to prevent the thread ends from wrapping around them when being drawn into the tube 32.

10 During transfer, any tension which may be created in the weft thread of the bobbin being transferred will tend to bend the tube 32 toward the magazine, curving the tube in the manner suggested in Figs. 5 and 7 to prevent breakage of the thread. On the immediately following pick a second stress may be set up in the thread which may cause further bending of the tube, but unwinding of the thread from its bobbin during shuttle flight will tend to produce sufficient slack in the thread so that the tube 32 can return from the dotted to the full line position in Fig. 6. When returning to normal position the tube 32 will move its mouth, and therefore the thread in it, forwardly from the dotted line position 50 of Fig. 6 to the full line position 51. This forward motion of the thread places it under the filling fork to support the tines 21 and permit continued loom operation.

By referring to Fig. 7 it will be seen that when the tube 32 bends toward the magazine the left hand part of the bore 34 thereof is convex and thread W must therefore lie along a considerable length of the interior of the rubber tube. Because of the high frictional resistance which the rubber offers to slipping of the thread the latter will be held closely against the interior of the tube and cause bending of the latter. It is to be understood, however, that the bending of the tube may not necessarily depend upon this frictional engagement with the thread, inasmuch as the latter will ordinarily be entangled with the mass of yarn Y in the accumulator and therefore be anchored within the cylinder 10.

I have found in actual operation that the tubular thread holder tends to hold the threads in the spaced relationship shown in Fig. 4, because of the fact that the forward free and unsupported end of the soft rubber tube 32 tends to vibrate under loom operation and thus effect constant readjustment of the threads to prevent their permanent entanglement.

From the foregoing it will be seen that I have provided a pneumatic thread holder having a yieldable intake member projecting normally in a direction transverse of the weft ends W and bendable toward the magazine to relieve any strains which may be created in the weft thread of the bobbin being transferred, either at the time of transfer or the pick immediately thereafter. It will also be seen that the bending of the tube 32 insures close frictional contact between the thread and the interior of the tube, thereby increasing the holding effort which the tube exerts on the thread. The tube 32 may be made either of natural or artificial rubber or similar material. Furthermore, the flange 36 near the mouth of the tube 32 spaces the threads for a short distance at least from the internal bore of a rubber tube, thereby permitting the inrushing air to reach all sides of the thread and direct it toward the cylinder 10. Also, the forward return motion of the tube from the dotted to the full line position shown in Fig. 6 serves to place the thread of the freshly transferred bobbin in a position favorable for cooperation with the filling

stop motion. It will further be seen that the resilient tube is so mounted as to have a free end which vibrates during loom operation and that the effect of this vibration is to space the weft ends and prevent them from becoming entangled.

Having thus described my invention it will be seen that changes and modifications may be made therein by those skilled in the art without departing from the spirit and scope of the invention and I do not wish to be limited to the details herein disclosed; but what I claim is:

1. In a weft replenishing loom having a lay and a filling fork extending rearwardly toward the path of the shuttle to be replenished from a magazine of reserve bobbins and subsequently picked in a direction from said group toward the fork, the reserve bobbins having weft ends extending therefrom toward a support mounted on the loom adjacent the magazine, that improvement comprising an elastic tubular thread holder which wherenin normal position projects forwardly from the support in a direction transverse of the weft ends and opposite to the direction in which the fork projects, said thread holder bending toward the group of reserve bobbins and toward the path of the shuttle when tension is created in the weft end of a reserve bobbin transferred into the shuttle and then picked toward the fork, return of the tubular thread holder to normal position moving said weft end forwardly to assist in placing said thread under said fork.

2. In a weft replenishing loom having a magazine provided with reserve bobbins from which weft threads extend toward a support mounted on the loom adjacent the magazine, the loom also having provision for transferring a reserve bobbin from the magazine into an exhausted shuttle, that improvement which comprises a resilient hollow member projecting from the support normally in a direction transverse of the weft threads which extend from the reserve bobbins toward the support, and means to create sub-atmospheric pressures within the hollow member to draw the weft threads thereinto, the hollow member yielding in a direction toward the reserve bobbins in response to tension created in the weft thread of a bobbin being transferred into the shuttle to reduce the liability of breakage of the last named weft thread.

3. In a weft replenishing loom having a magazine provided with reserve bobbins from which weft threads extend toward a support mounted on the loom adjacent the magazine, the loom having a thread accumulator containing a mass of yarn and having means to create sub-atmospheric pressures within the accumulator, the loom also having provision for transferring a reserve bobbin from the magazine into an exhausted shuttle, that improvement which comprises a soft and elastic tubular member projecting from the accumulator in a direction normally transverse of the direction in which the weft threads extend from the reserve bobbins toward the support and having the interior thereof in pneumatic communication with the interior of the accumulator, sub-atmospheric pressures within the accumulator creating sub-atmospheric pressures within the tubular member to draw the weft threads of the reserve bobbins into said tubular member and entangle them with the mass of yarn in the accumulator, the tubular member yielding toward the reserve bobbins in response to tension created in a weft thread extending from the mass of yarn to a reserve bobbin being inserted into the exhausted shuttle.

4. In a weft replenishing loom having a magazine provided with reserve bobbins from which weft threads extend toward a support mounted on the loom adjacent the magazine, the loom having a thread accumulator containing a mass of yarn and having means to create sub-atmospheric pressures within the accumulator, the loom also having provision for transferring a reserve bobbin from the magazine into an exhausted shuttle, that improvement which comprises a soft rubber tube projecting from the accumulator in a direction normally transverse of the direction in which the weft threads extend from the reserve bobbins toward the support, the interior of the rubber tube communicating pneumatically with the interior of the accumulator so that sub-atmospheric pressures within the accumulator will create sub-atmospheric pressures within the rubber tube to draw the weft threads into said rubber tube to entangle said weft threads with the mass of yarn in the accumulator and exert a normal tension on said weft threads, said rubber tube yieldable because of its resilience toward the reserve bobbins when any thread extending from the reserve bobbins into the tube is subjected to abnormal tension.

5. In a weft replenishing loom having a magazine provided with a group of reserve bobbins from which weft threads extend toward a support mounted on the loom adjacent the magazine, and wherenin a depleted shuttle is replenished with a reserve bobbin drawn from the magazine and subsequently picked in a direction away from the magazine and support, that improvement which comprises a hollow elastic member projecting from the support normally in a direction transverse of the direction in which the weft threads extend from the reserve bobbins toward said support, and means to create sub-atmospheric pressures within the hollow member to draw the weft threads into said member, the latter yielding in a direction toward the reserve bobbins when the thread of a reserve bobbin with which the shuttle has been replenished is subjected to tension incident to picking of the shuttle in a direction away from the magazine and support.

6. In a weft replenishing loom having a magazine provided with a plurality of reserve bobbins from which weft threads extend toward a support mounted on the loom adjacent the magazine, the loom operating with a shuttle to be replenished when exhausted of weft with a bobbin from the magazine and subsequently picked in a direction from a position adjacent to the magazine opposite to the direction in which the weft threads extend from the reserve bobbins toward the support, that improvement which comprises a soft rubber tube projecting from the support in a direction transverse of the weft threads, and means to create sub-atmospheric pressures within the rubber tube to draw the weft threads thereinto and hold said weft threads in the rubber tube, the latter yieldable in a direction toward the reserve bobbins when the weft thread of the bobbin with which the shuttle has been replenished is subjected to tension incident to picking the shuttle.

7. In a weft replenishing loom having a magazine provided with reserve bobbins from which weft threads extend toward a support mounted on the loom adjacent the magazine, that improvement which comprises a tubular member including elastic rubber in its construction and

mounted on the support and projecting therefrom in a direction normally transverse of the direction in which the weft threads extend from the reserve bobbins toward the support, and means to create sub-atmospheric pressures within in the tubular member to draw the weft threads into and hold them in the tubular member under a normal tension, said tubular member yielding toward the reserve bobbins when an abnormal tension exists in any thread extending from a reserve bobbin into said tubular member and the latter bending to assume a curved form and thereby cause close contact between the thread under abnormal tension and an interior surface of the tubular member extending along a relatively long surface of said tubular member.

8. In a weft replenishing loom having a magazine provided with reserve bobbins from which weft threads extend toward a support mounted on the loom adjacent the magazine, that improvement which comprises a resilient tube having an intake mouth and projecting normally from the support in a direction transverse of the weft ends, and having an internal bore of given diameter, a flange extending around the intake mouth and providing a thread receiving orifice of a diameter less than said given diameter, and means to create sub-atmospheric pressures within the yieldable tube to draw the weft threads through the orifice and into the yieldable tube, and said flange holding the weft threads spaced from that part of the internal bore of the resilient tube adjacent to said flange, whereby air drawn into the tube acts on all sides of the weft threads extending from the flange into said tube.

9. In a weft replenishing loom having a lay and a filling fork extending rearwardly toward the path of the shuttle along the lay, the loom having a magazine provided with a group of reserve bobbins from which weft threads extend toward a support mounted on the loom adjacent the magazine, the shuttle to be replenished with a reserve bobbin from the magazine and subsequently picked in a direction from the magazine toward the fork, and the support being on that side of the magazine opposite the fork, that improvement which comprises a resilient tubular member projecting from the support in a direction transverse of the weft threads which extend from the magazine toward the support, and means to create sub-atmospheric pressures within in the tubular member to draw the weft threads

into said tubular member, tension in the weft thread of a bobbin inserted into the shuttle which is subsequently picked toward the fork causing said tubular member to move to an abnormal position and in a direction toward the magazine and toward the shuttle path, return of the tubular member to normal position moving the weft thread in a direction which assists placement of the thread of the bobbin which has been inserted into the shuttle under the fork.

10. In a weft replenishing loom having a magazine provided with reserve bobbins from which weft threads extend toward a support mounted on the loom adjacent to the magazine, that improvement which comprises a resilient tubular member one end of which is held by the support and the other end of which is free from the support and extends away from the latter in a direction transverse of the direction in which the weft threads extend from the reserve bobbins toward the support, and means to create sub-atmospheric pressures within the tubular member to draw the weft threads into and hold them in said tubular member under normal tension, said other free end of the tubular member being subject by reason of its resilience to vibration due to loom operation and acting by reason of said vibration to subject the weft threads to constant readjustment to prevent their entanglement in the tubular member.

11. In a weft replenishing loom having a magazine provided with reserve bobbins from which weft threads extend toward a support mounted on the loom adjacent the magazine, that improvement which comprises an inherently resilient hollow member mounted on the support and the normal position of which is transverse of the direction in which the weft threads extend from the reserve bobbins toward the support, said hollow member movable from normal position toward the reserve bobbins and tending by the inherent resilience thereof to return to normal position, and means to create sub-atmospheric pressures within the hollow member to draw the weft threads into and hold them in the hollow member under normal tension, said hollow member being yieldable from normal position toward the reserve bobbins when abnormal tension exists in any given thread extending from the reserve bobbins into said hollow member to reduce the liability of weft thread breakage due to the abnormal tension.

RICHARD G. TURNER.
